UNITED STATES PATENT OFFICE.

NORMAN W. HALSEY, OF NEW YORK, N. Y., ASSIGNEE TO SOAP FEEDER CORPORATION, OF NEW YORK, N. Y., A CORPORATION OF NEW YORK.

CLEANING MATERIAL FEEDER FOR WASHING MACHINES OF THE SPRAY TYPE.

Application filed December 14, 1922. Serial No. 606,770.

This invention relates to improvements in cleaning material feeders for washing machines of the spray type.

One of the objects of this invention is to provide a washing machine of the spray type with a device operable by a portion of the water distributed or sprayed by the spraying nozzles for measuring and charging the wash-water with cleansing material.

Another object of this invention is to provide a washing machine of the spray type with feeding means which will automatically during the spraying operation of the machine charge the wash water with a quantity of cleansing material measured in relation to the amount of water sprayed inside of the machine by the spraying nozzles and therefore in proportion to the wash water utilized in such machine.

Another object of this invention is to economize cleaning material by the automatic delivery thereof to the wash water in the exact proportion to give such water the most efficient cleaning strength.

Another object of the invention is to provide a feeding device that will enable the automatic charging of the wash water for a relatively long period of time, thus doing away with the necessity of feeding loose cleaning material into the tank.

Another object of my invention is to provide a washing machine of the spray type with an automatic feeding device that will so automatically charge and keep the wash water charged at the most efficient strength without attention of any kind by the operator, and which will automatically stop feeding the cleaning material or charging the wash water in the tank when the water passed through the spraying nozzles inside the machine is shut off.

Another object of my invention is to enable an automatic slow feeding or drip and the automatic cut off of a solution of a concentrated powdered cleaning material and the feeding of an exceedingly small quantity of this concentrated solution to the wash water in proportion to the amount of water passed through the nozzles of the machine, and therefore in proportion to the amount of work which is being done in the machine.

Another object of this invention is to produce a feeding device of the character

specified in which the proportion of cleaning material to the water sprayed may be varied and the proportionate amount increased or decreased to suit varying conditions of work.

Another object of my invention is to provide a washing machine of the type specified with a feeder for cleaning material which will be an independent unit and not connected by piping to the water supply, and which may therefore be removed and replaced at will without special fittings and attachments of any kind.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a cross section of a cleaning machine of the spray type embodying my automatic feeder actuated by the spray water.

Fig. 2 is a cross section of the automatic feeding attachment shown in Fig. 1;

Fig. 3 is a section on the line 3—3 of Fig. 2; and

Fig. 4 is a view in plan of the inlet-valve mechanism when the cover is removed and turned inner side up.

Referring now to these drawings, which illustrate a preferred embodiment of my invention, 1 indicates the outer casing of a dish washing machine of the spray type which is provided at its lower end with a wash tank 2 above which is supported a strainer 3 and a dish rack 4, in which rack dishes are suitably positioned.

Within the casing 1 is provided an upright supply pipe 5 which is provided with the usual laterally-extending arms 5^a and 5^b, on both of which are revolvably mounted upper and lower wash-nozzles 6 and 6^a respectively, which nozzles are designed to spray or diffuse water on, against and between dishes 4^a in the rack 4. This sprayed or diffused water finally falls down through the strainer pan 3 and into the tank 2, after which such wash-water is pumped by the pump 7 upwardly through the upright pipe 5 and nozzles 6 so as to form a continuous circulation and distribution or diffusion in

contact with the dishes of such wash water. After initial washing of the dishes by such wash-water, the dishes are usually sprayed through the rinsing-nozzles 8. The addition of this rinsing water to the wash-water in the tank maintains the wash-water in proper condition for use, the surplus water and grease passing out of the tank through the overflow pipe 2^a.

- 10 The foregoing is a description of one form of washing machine of the spray type, and standing by itself alone, constitutes no part of my invention which consists, however, in providing a machine of this type with a 15 feeder 9 for cleaning material which utilizes a portion of the water distributed or sprayed by the spraying nozzles for its actuation and therefore enables an extremely slow automatic feed to be provided and also an automatic cut-off when the machine is stopped. 20 In the preferred form of my invention shown, I use such a portion of the sprayed water for dissolving powdered cleaning material contained within the feeder, and provide for the free discharge of such solution 25 as formed from the feeder into the wash water which will be charged with a quantity of such cleaning material in proportion to the amount of such distributed or sprayed 30 water admitted to the feeder, and the portion of such sprayed water so utilized may be regulated by increasing or diminishing the size of the inlet aperture for such sprayed or distributed water.
- 35 In the preferred embodiment of my invention, my automatic feeder comprises an independent unit which may be inserted or supported at any place within the area of distribution or spray of water by the spraying nozzles and, as shown, consists of a 40 cylindrical container 10 which is preferably formed of a non-corrodible metal and is loaded or charged to a predetermined point, as for example to the broken line 11 with 45 a suitable powdered cleaning material which is readily dissolved in water. Such material is usually intensely concentrated and therefore expensive and only a relatively small quantity of the same is required to 50 charge the wash water so as to give the same a cleaning strength of the highest efficiency and any additional material fed to the wash-water is wasted. By the use of my feeding device, which utilizes in its operation a small 55 fraction of the sprayed or distributed water, I am enabled to charge the wash water with the very small quantity of such material in solution that is necessary to give such water the highest cleaning strength. The use of 60 the material is thus economized. I am furthermore enabled to accomplish these purposes without attention of any kind by the operator after the feeder is loaded and inserted into the machine.
- 65 In the preferred form of my invention I

provide said container 10 with a removable cover 10^a having a water-shedding surface which is perforated to provide a relatively small inlet aperture 12 to admit a predetermined quantity of the sprayed or diffused water. Obviously when the water distributed or diffused by the spraying nozzles falls on the water-shedding top surface of the cover 10^a a small quantity of such water will enter any inlet orifice or perforation in the 75 top or cover and the quantity admitted will be determined by the size of the inlet orifice in the cover, and the water so admitted will fall down upon the powdered material, a portion of which powdered material will be 80 dissolved and the amount of such solution will be definitely determined by the quantity of water admitted which is, as aforesaid, determined by the size of the opening through the cover 10^a of the container. This 85 dissolved portion will pass down to the bottom of the container and I provide a series of discharge openings which are preferably large enough to permit free discharge of the dissolved material but small enough 90 to retain the material in its powdered form. As illustrated, I provide one series of discharge openings 13 around the edge of the bottom of the container and preferably provide another series 14 of discharge apertures 95 through the side walls contiguous to the bottom of the container. As illustrated, the side apertures 14 are provided with shields 15 open at its bottom.

In the preferred form of my invention I 100 provide means whereby the size of the inlet opening may be varied at will and as shown employ a plate valve 16 mounted to rotate about a pivot 17 and having a series of apertures 18 of varying size so that upon a 105 rotation of the valve plate the size of the inlet opening therethrough which registers with the perforation in the cover may be varied. The variation of such opening, however, is not absolutely essential as an 110 opening or openings of any predetermined size may be made in the cover so as to suit the conditions in a given machine.

In operation, the small inlet opening or orifice 12 will allow an exceedingly small 115 quantity or portion of the water distributed or sprayed by the nozzles to pass through said opening and drip into the container and into the powdered material. This small portion of water then dissolves a part of the 120 powdered material, passes in solution through the powdered cleaning material to and through the discharge openings 13. In the event that these discharge openings 13 become clogged from grease or other extraneous matter, the cleaning solution will rise above the same and pass out through the discharge openings 14. After the solution passes through the discharge openings 125 it is fed into the wash water in the tank so 130

as to charge the same to an efficient degree with such powdered and concentrated cleansing material.

It is also apparent that by varying the size 5 of the inlet aperture through the cover 10* by means of the regulating plate valve 16 the amount of water admitted may be regulated or controlled, and this in turn will control the quantity of cleaning material 10 dissolved and discharged so as to suit varying operating conditions. Once the proper size of hole is selected, however, to suit a particular machine or given conditions this size of hole may be maintained permanently, 15 and it is also apparent that different feeders may be provided with varying holes to suit varying conditions and varying sizes of machines and classes of work.

Having described my invention, I claim:—
20 1. A cleaning material feeder for washing machines adapted to operate within a stream or shower of water, comprising a container having water shedding walls for confining powdered soluble cleaning material, said container being provided on that side upon which the water impinges with an aperture for receiving a relatively small portion of the impinging water and directing it to the material within the container to form 25 a solution therewith and means to regulate the effective size of said aperture, said container also being provided on another side with apertures for allowing the liquid cleansing solution to escape while retaining 30 the powdered material.

2. A cleaning material feeder for washing machines adapted to operate within a stream or shower of water, comprising a container having water shedding walls for 40 confining powdered soluble cleaning material, said container being provided on that side upon which the water impinges with an aperture for receiving a relatively small portion of the impinging water and directing 45 it to the material within the container to form a solution therewith and means to regulate the effective size of said aperture, said means consisting of a movable plate provided with an aperture adapted to coincide 50 with the aperture in the wall of the container, said container also being provided on another side with apertures for allowing the liquid cleansing solution to escape while retaining the powdered material.

55 3. A cleaning material feeder for washing machines adapted to operate within a stream or shower of water, comprising a container having water shedding walls for confining powdered soluble cleaning material, said container being provided on that side upon which the water impinges with an aperture for receiving a relatively small portion of the impinging water and directing it to the material within the container to form a solution 60 therewith and means to regulate the ef-

fective size of said aperture, said means consisting of a rotatable disc provided with an aperture adapted in various positions of the disc to coincide with the aperture in the wall of the container, said container also being 70 provided on another side with apertures for allowing the liquid cleansing solution to escape while retaining the powdered material.

4. A cleaning material feeder for washing machines adapted to operate within a stream or shower of water, comprising a container having water shedding walls for confining powdered soluble cleansing material, a removable cover for said container constituting the principal wall upon which the water impinges, said cover having an aperture for receiving a relatively small portion of the impinging water and directing it to the material within the container to form a 80 solution therewith and means to regulate the effective size of said aperture, said container also being provided on another side with apertures for allowing the liquid cleansing solution to escape while retaining the powdered material.

5. A cleaning material feeder for washing machines adapted to operate within a stream or shower of water, comprising a container having water shedding walls for confining 85 powdered soluble cleaning material, a removable cover for said container constituting the principal wall upon which the water impinges, said cover having a convex upper surface and an aperture at its crown for 90 receiving a relatively small portion of the impinging water and directing it to the material within the container to form a solution therewith and means to regulate the effective size of said aperture, said container 95 also being provided on another side with apertures for allowing the liquid cleansing solution to escape while retaining the powdered material.

6. A soluble material feeder for washing machines adapted to operate within a stream or shower of water, comprising a container for confining a solid soluble material, having upper walls comprising means to shed the major portion of the water impinging 110 thereagainst but to pass a small portion of the impinging water to the material within the container to form a solution therewith, and a convex bottom wall having apertures adjacent its outer edges adapted to pass the 115 solution but to retain the solid material.

7. A soluble material feeder for washing machines adapted to operate within a stream or shower of water, comprising a container for confining a solid soluble material, having upper walls comprising side walls and a top cover wall comprising means to shed the major portion of the water impinging 120 thereagainst but to pass a small portion of the impinging water to the material within 125

the container to form a solution therewith, and a bottom wall for retaining the solid material, said side walls having apertures adjacent their lower edges adapted to pass the solution but to retain the solid material.

8. A soluble material feeder for washing machines adapted to operate within a stream or shower of water, comprising a container for confining a solid soluble material, having upper walls comprising side walls and a top cover wall comprising means to shed the major portion of the water impinging

thereagainst but to pass a small portion of the impinging water to the material within the container to form a solution therewith, and a bottom wall, said side walls having apertures adjacent their lower edges adapted to pass the solution but to retain the solid material, and shields over said apertures adapted to shed the impinging water.

In testimony whereof, I have signed my name to the foregoing specification.

NORMAN W. HALSEY.
